CLAIM

The ornamental design for a shoe outsole bottom as shown and described.

DESCRIPTION

FIG. 1 is a front perspective view of a shoe outsole bottom in accordance with my design;

FIG. 2 is a right side view thereof;

FIG. 3 is a left side view thereof;

FIG. 4 is a front view thereof;

FIG. 5 is a rear view thereof;

FIG. 6 is a top view thereof; and,

FIG. 7 is a bottom view thereof.

The surface textures, whitewashed portions, and shading form no part of the claimed design. A dot-dash line is provided to define the boundary between the midsole periphery and outsole bottom and forms no part of the claimed design. The dash-dash broken lines shown in the drawings represent environmental structure of parts of the shoe and form no part of the claimed design.
